CLAIM

The ornamental design for an intercommunication system, as shown and described.

DESCRIPTION

FIG. 1 is a front elevational view of an intercommunication system showing our new design;

FIG. 2 is a back elevational view thereof;

FIG. 3 is a top plan view thereof;

FIG. 4 is a bottom plan view thereof;

FIG. 5 is a right side elevational view thereof;

FIG. 6 is a left side elevational view thereof; and,

FIG. 7 is a perspective view taken generally from the top, front, left-hand side thereof.

High-quality electronic copies of the drawings are available in the Office's electronic record of this application.
